UNITED STATES PATENT OFFICE.

FITZALLAN B. WILLIAMS, OF CHICAGO, ILLINOIS.

FASTENING FOR KNOCKDOWN FURNITURE.

SPECIFICATION forming part of Letters Patent No. 793,255, dated June 27, 1905.

Application filed September 21, 1904. Serial No. 225,816.

To all whom it may concern:

Be it known that I, FITZALLAN B. WILLIAMS, of Chicago, in the State of Illinois, have invented certain new and useful Improvements 5 in Fastenings for Knockdown Furniture, of which the following is a specification.

The invention relates to means for attaching or securing together the separable parts of articles of knockdown furniture, and the 10 improvement comprises companion parts having meeting surfaces with attaching devices, and bearing-surfaces adapted to fit upon and be secured to the parts of such articles.

The object of the improvement is to provide 15 a device of this character which will be conveniently and generally applicable for connecting separable parts of tables, desks, folding bedsteads, partitions, boxes, cases, or any parts ordinarily connected with screws, nails, 20 glue-blocks, corner-irons, mortises, and the like, which are assembled to form the complete article and which it may be desirable to separate occasionally for shipment, storage, or other purposes. I have attained this 25 object by the means illustrated in the accompanying drawings, in which—

Figure 1 is an elevation showing two separable parts of such an article in fragment connected by a fastening device containing my 30 invention and shown in edge view. Fig. 2 is a view of the same parts, but shows one member of the article and of the fastening device in plan view as seen when looking at Fig. 1 in an upward direction. Fig. 3 is a section 35 taken on the line 3 3 of Fig. 2. Fig. 4 is a detail showing an end or edge view of the detached male part of the device. Fig. 5 is a detail showing a bottom view of the detached female part. Fig. 6 is a detail showing a 40 bottom view of a detached locking-piece, and Fig. 7 is a detail showing an end view of the said locking-piece.

In the drawings the numerals 1 and 2 designate connected parts of the article of furniture. The male part 3 is secured by screws 45 4 to the part 2 with its bearing-surface upon the same, and the female part 5 is secured with its bearing-surface resting upon the part 1, as shown in Figs. 1 and 2. Flush with the edge 50 6 of part 3 is a projection 7, which has a flat

side extended in the same plane with said edge. From said flat side a pin 8 extends, said flat side and edge 6 forming the meeting surface of said part 3 and being the head of the pin. Said pin has a notch or groove 55 9, Fig. 3, in the face side thereof near the end.

The bearing-surface of part 5 is seen in Fig. 5. It has a flat portion along its rear part adapted to fit snugly upon the part 1 and a 60 raised or recessed portion 10 at center projecting in front. It has a perforation 11 adapted to receive the pin 8 of part 3, the perforation at the rear coming near the rear edge, or in some instances cutting through 65 the edge, as seen in the illustration. The top side of part 5 around said perforation is made flat to fit against the edge and flat side of projection 7 and constitutes the meeting surface of said part 5. A rotatable locking-piece 12 70 is adapted to fit under the raised or recessed edge 10 and be secured there by a screw 13, which passes through perforations 14 and 15 and enters the part 1. Said locking-piece has an inclined or thread-like flange or cam 16, 75 which traverses the perforation 11 and is provided with a recess 17. Preferably a perforated lever or handle 18 is provided for rotating said locking-piece and securing it in any desired position by means of a nail or screw 80 set through its perforation into the part 1. The outer end of the lever being tapped with a hammer may be forced round until the cam will jam up so tight as to stay in place without any nail or screw, and the nail or screw 85 may be applied against the side of a lever not perforated to hold it from turning the same as if in the perforation. When the recess 17 is turned forward to coincide with the perforation 11, the pin 8 can be entered into said 90 perforation, so that the meeting surface of part 3 will impinge upon the meeting surface of part 5, and by now turning said locking-piece back the thread-like flange or cam will enter the groove 9 of said pin and bear increasing 95 upon the bearing-point 19, Fig. 3, at the inner side of said groove as it is turned back, tending to draw said pin farther into said perforation and causing the meeting surface of part 3 to bear so hard upon the meet- 100

ing surface of part 5 as to bind said parts rigidly together and to hold the attached parts 1 and 2 as firmly together as if dovetailed or secured with screws or nails, corner-irons, or 5 glue-blocks.

The invention in this case consists, generally, of a pair of companion parts, each provided with screw-holes, a bearing-surface adapted to fit upon one of the parts of the article to be connected, and a meeting surface adapted to fit upon the opposite companion part for holding the pair firmly in the desired relative position to one another, and a part having a revoluble cam, one of said companion parts having a perforation or recess traversed by the revoluble cam, which is adapted to be set in a fixed position, and the other of said parts having a pin or extension adapted to enter said perforation and provided with a 10 lug serving as a bearing-surface for the cam to draw the pin into the perforation and hold it there for binding said companion parts firmly together upon their meeting surfaces, substantially as described.

What is claimed is—

1. A device of the class described comprising a pair of companion parts and a part having a revoluble cam, each of the companion parts having a bearing-surface and a meeting surface and screw-holes, one of said parts having a perforation and the other an attaching-pin adapted to enter the perforation and provided with a lug, and the cam being adapted to traverse said perforation and bear upon the lug, as specified. 25

2. A device of the class described comprising a plate 3 provided with screw-holes, a meeting surface 6, 7, and a grooved pin 8 extended from said meeting surface, a plate 5 provided with screw-holes, a meeting surface, a recess 10 and perforation 11, and a rotatable locking-piece 12 provided with a recessed, thread-like cam 16 and lever 18, as specified. 30 40
